UNITED STATES PATENT OFFICE.

ED M. JENKINS, OF ITALY, TEXAS.

SANITARY TELEPHONE-MOUTHPIECE.

1,215,377.

Specification of Letters Patent.

Patented Feb. 13, 1917.

Application filed January 19, 1915. Serial No. 3,033.

To all whom it may concern:

Be it known that I, ED M. JENKINS, citizen of the United States, residing at Italy, in the county of Ellis and State of Texas, have invented certain new and useful Improvements in Sanitary Telephone-Mouthpieces, of which the following is a specification.

This invention relates to new and useful 10 improvements in sanitary telephone mouth-pieces.

The object of the invention is to provide certain improvements in the construction and arrangement of the telephone mouth-piece previously patented by me, which improvements are; the provision of an outer shell of regular contour and without a depending receptacle; the provision of means for storing a disinfectant within the said 20 outer shell; means for fastening the mouth-piece on a telephone transmitter and at the same time adjusting it so the nipple remains upright and also for drawing the parts into firm engagement with each other; and the 25 provision of a fibrous member for absorbing the disinfectant; and also the provision of means for insulating the entire mouth-piece from the transmitter.

A still further object of the invention is 30 to provide a device of the character described that will be strong, durable, efficient, and simple and inexpensive to construct; also one in which the several parts will not be likely to get out of working order.

With the above and other objects in view, 35 the invention has relation to certain novel features of construction and operation, an example of which is described in the following specification and illustrated in the accompanying drawings, wherein:

Figure 1 is a side elevation of a transmitter equipped with the improved mouth-piece,

Fig. 2 is a side elevation of the inner shell,

Fig. 3 is a side elevation of the intermediate shell,

Fig. 4 is a side elevation of the outer shell,

Fig. 5 is a longitudinal sectional view of 50 the mouth-piece,

Fig. 6 is a transverse sectional view taken on the line $x-x$ of Fig. 5,

Fig. 7 is a side elevation of the coupling and insulating member,

Fig. 8 is a view of a modified form of

mouth-piece, a portion being illustrated in section,

Fig. 9 is a transverse sectional view taken on the line $a-a$ of Fig. 8,

Fig. 10 is a view of another form, and

Fig. 11 is a view of a still further modification.

In the drawings the numeral 1 in each figure designates an outer metallic shell, 2 an intermediate shell and 3, an inner shell. 65 The outer shell 1 has a general cylindrical shape open at its front end and having an inwardly directed flange 4 at its rear end which provides a central opening. The flange 4 is turned outward around the central opening as is indicated at 5 and a tapering collar formed. The shell 1 proper is merged into the flange by gradual curves and the intersection forms an annular receptacle or pocket which receives a ring of 75 fibrous material 6 as shown.

The intermediate shell 2 is frusto-conical and provided with a laterally directed flange 10 at its front end, said flange fitting snugly within the shell 1 and having a notch 7 receiving a projection 8 from the shell 1; whereby said shell 2 is held against rotation in shell 1 and caused to be inserted in a certain position. With the shell 2 in position only a portion of the wall is perforated, that 85 being at the underside as shown. These perforations 9 are in a cluster and are the only means of passage for the fumes disseminating from a disinfectant stored in the ring 6.

The inner shell 3 has an annular roll 90 flange 11 at its front end which engages over both the front edge of the outer shell and the flange 10 of the shell 2. The shell 3 is contracted and gradually curved inward toward its inner end where it is provided with an internal screw threaded annular boss 12. The inner end of the shell 3 frictionally engages in the collar 5 of the outer shell, but terminates short of the outer edge of said collar. The intermediate shell 2 has 100 its inner end projecting into the crotch formed by the intersection of the inner and outer shells as is best shown in Fig. 5. The inner shell 3 has a plurality of spaced perforations whereby the fumes passing through 105 the intermediate shell are disseminated in the inner shell.

The shells are spaced apart as shown and this spacing is a direct result of the particular shapes, but it is to be understood that the 110

shapes may be varied and the intermediate shell entirely omitted if desired as shown in Fig. 11 where the ring 6 is held in place by a perforated washer 14 fitting snugly on the inner shell. The ring 6 in both forms is confined to the rear portion of the outer shell, thus providing a space in front as shown.

A nipple 15 is provided on the outer shell 10 and is confined to that portion receiving the ring 6 and normally is positioned at the upper side of the shell. This nipple is closed by a screw cap 16. By removing said cap the ring of fibrous material is exposed 15 and liquid disinfectant may be introduced and stored in the ring without disturbing the adjustment of the parts or the position of the mouth-piece on the transmitter. The nipple and cap however may be omitted if 20 desired as shown in Fig. 11 and the ring saturated by disconnecting the shells.

One of the very essential and novel features of the invention is a coupling 20 having a serrated periphery and also provided with 25 integral collars 21 and 22 projecting from opposite sides. These collars are externally screw threaded, the collar 21 being adapted to be screwed into the ordinary telephone transmitter and the collar 22 being screwed 30 into the boss 12 of the inner shell. The inner end of the inner shell terminating short of the outer edge of the collar 5 it is obvious that when the coupling is screwed into the boss it will bear against the collar 35 and draw the inner shell into said collar whereby the roll flange 11 is drawn tight over the outer end of the outer shell and the parts firmly fastened together. In attaching the mouth-piece to the transmitter the 40 coupling is not screwed up tight into the shell but left loose so that the collar 21 can be screwed into the transmitter and the nipple adjusted in an upright position before finally tightening the parts which may 45 be accomplished by rotating the inner shell. That portion of the coupling 20 within the collar 22 is perforated the same as the corresponding portion of the ordinary mouth-piece. The coupling is preferably made of 50 some insulating material whereby the entire mouth-piece is insulated from the transmitter and the liability of an electrical shock obviated.

In Figs. 8 and 9 I have shown a slightly 55 modified form which involves an outer shell 30 having a collar 31 similar to the collar 5 and a nipple 32 provided with a screw cap 33. The shell is divided into two members 60 A and B respectively, the member A carrying the nipple and the collar and receiving a fibrous ring 34 which is confined by a perforated washer 35 similar to the washer 14. An inner shell 36 is formed integral with the member A and has its inner end frictionally 65 engaging in the collar 31, the member A fit-

ting snugly in the member B and bearing against the washer. The same coupling 20 is employed and screwed into a boss 37 in the inner shell. Slits 38 in the inner shell communicate with the annular space between 70 the shells and forward of the washer. The fumes from the disinfectant stored in the ring 34 are disseminated through the slits into the inner shell.

It is obvious that this invention can be 75 applied to the mouth-piece used in telephone operators' breast sets as shown in Fig. 10. An outer shell 40 is provided and also has a collar 41 which receives an intermediate shell 42 having perforations 43 at one side. 80 A fibrous washer 44 surrounds the shell 42 within the outer shell. A flanged closure provided with a central opening is removably secured on the outer shell. The mouth-piece 46 passes through the closure 45, shell 85 42 and collar 41 and corresponds to the inner shell of Fig. 5. Packing washers 47 and 48 are confined at the ends of the shell 42 and closely embrace the mouth-piece so that the fumes cannot escape through either 90 of the openings. That portion of the mouth-piece confined between the washers has perforations 49 whereby the fumes from the disinfectant escape into the mouth-piece. 95

It is to be understood that in using these devices a suitable disinfectant is stored in the outer shell and the fumes escaping through the various perforations and openings find their way into the inner shell or 100 tubular member and perform their function. The disinfectant is renewed from time to time. Where an intermediate shell is used it is perforated in such a manner that a surplus of liquid disinfectant cannot run down into the inner shell. 105

The invention is presented as including all such modifications and changes as properly come within the scope of the appended claims.

What I claim, is:

1. In a telephone transmitter mouth-piece, the combination of an inner shell, an outer shell equipped with means for storing a disinfectant therein, the inner shell being tapered and having its inner end engaging in the end wall of the outer shell, said inner shell being constructed to disseminate the fumes from the disinfectant, and a coupling 115 engaging the outer shell and attached to the inner shell and fastening said shells together, said coupling being constructed to engage a telephone transmitter and support the mouth-piece. 120

2. In a telephone transmitter mouth-piece, the combination of an outer tubular member, an inner tubular member, an intermediate tubular member disposed between the other two members and within the outer member, a disinfectant storing member surrounding the intermediate member within 130

the outer member, the intermediate member being constructed to admit the disinfectant fumes from the outer member, the members being arranged so that the fumes cannot escape except through the intermediate member, the inner member having provision for disseminating the disinfectant fumes therein, and means for fastening the members together.

- 5 10. 3. In a telephone transmitter mouth-piece, the combination of an outer shell, an inner shell separate from but fitting within the outer shell, the outer shell having a tapering collar at its inner end, the inner shell having its inner end frictionally engaging in the collar of the outer shell, and a coupling member engaging in the inner shell and bearing against the outer shell whereby the inner shell is drawn within the outer shell, said coupling member being separate and distinct from the shells and having provision for engaging in a telephone transmitter, the outer shell having provision for storing a disinfectant between the same and
- 15 20. 25. the inner shell.

4. In a sanitary telephone transmitter mouth-piece, the combination of an outer shell having provision for storing a disinfectant therein, a tapering collar provided on the inner end of the outer shell, an inner shell fitting within the outer shell and having its inner end frictionally engaging in the collar, an intermediate shell disposed within the outer shell and surrounding the inner shell, said intermediate shell having its inner end projecting into the joint formed by the inner ends of the outer and inner shells, and a coupling member separate from the shells engaging the inner end of the inner shell and bearing against the outer shell whereby the inner shell is drawn within the outer shell, said coupling member having provision for engaging in a telephone transmitter.

- 45 5. In a telephone transmitter mouth-piece, the combination of an outer tubular member, an inner tubular member, an intermediate tubular member disposed between the other two members and within the outer member, a disinfectant storing member surrounding the intermediate member within

the outer member, the intermediate member being constructed to admit the disinfectant fumes from the outer member, the members being arranged so that the fumes cannot escape except through the intermediate member, the inner member having provision for disseminating the disinfectant fumes therein, and a separate coupling member engaging the inner shells and fastening all the shells together, said coupling having means for engaging a transmitter.

6. In a telephone transmitter mouth-piece, the combination of a pair of shells one fitting within and movable with relation to the other, the inner shell having a laterally extending flange overhanging and engaging the outer end of the outer shell, the inner end of the inner shell frictionally engaging in the inner end of the outer shell, and an adjustable coupling member engaging the inner end of the inner shell and bearing against the inner end of the outer shell, whereby the inner shell is drawn into the outer shell and a frictional joint made at the inner ends while the flange of the former embraces the outer edge of the latter.

7. In a telephone transmitter mouth-piece, the combination of a substantially cylindrical outer shell having its inner end closed except at the center, a tapered inner shell fitting within the outer shell and movable relatively thereto, the inner shell closing the outer end of the outer shell and projecting into the central portion of the inner end of the outer shell whereby the inner end of the latter is closed, the tapered inner shell providing an annular chamber in conjunction with the end wall of the outer shell, within the outer shell, a disinfectant member occupying a portion of the chamber between the shells, and an adjustable coupling member impinging the outer shell and engaging the inner shell whereby the latter is wedged into the former and the chamber therebetween sealed.

In testimony whereof I affix my signature in presence of two witnesses.

ED M. JENKINS.
